CLAIM

The ornamental design for a column pipe, as shown and described.

DESCRIPTION

This application contains subject matter related to the following co-pending U.S. design patent applications:

Application Ser. No. 29/594,886, filed herewith and entitled "Column"; and

Application Ser. No. 29/594,889, filed herewith and entitled "Column End Cap".

FIG. 1 is a front and top perspective view of a column pipe according to the design;

FIG. 2 is a front elevational view thereof;

FIG. 3 is a right side elevational view thereof;

FIG. 4 is a top plan view thereof; and,

FIG. 5 is a cross-sectional view thereof taken along line 5-5 of FIG. 2.

A rear elevational view is the same as the front elevational view.

A left side elevational view is the same as the right side elevational view.

A bottom plan view is the same as the top plan view.
